UNITED STATES PATENT OFFICE

114,889

DESIGN FOR A COMBINED DISPLAY CARTON AND CARRIER

Thomas R. Campbell, Elmira, N. Y., assignor to Corning Glass Works, Corning, N. Y., a corporation of New York

Application March 1, 1939, Serial No. 83,284

Term of patent 14 years

To all whom it may concern:

Be it known that I, Thomas R. Campbell, a citizen of the United States of America, residing in the city of Elmira, county of Chemung, and State of New York, have invented a new, original, and ornamental Design for a Combined Display Carton and Carrier, of which the following is a specification, reference being had to the accompanying drawing, forming part thereof.

In the drawing:

Fig. 1 is a perspective view of a combined display carton and carrier showing my new design;

and

Fig. 2 is an end view thereof.

The side and end of the carton which are obscured in Fig. 1 are substantially identical with the side and end which are disclosed therein.

I claim:

The ornamental design for a combined display carton and carrier, as shown and described.

THOMAS R. CAMPBELL.
